UNITED STATES PATENT OFFICE.

LAURA L. MILLRING, OF NEW YORK, N. Y.

TOILET ARTICLE.

Application filed December 11, 1926. Serial No. 154,159.

This invention relates to toilet articles and more particularly to receptacles for cosmetics and appliances therefor.

One of the objects of this invention is to provide a simple and practical receptacle for compactly housing cosmetics and appliances therefor, and to provide a receptacle of the above nature in which the most necessary cosmetics and appliances therefor may be made readily and conveniently available or accessible, thereby to expedite the application of the cosmetics. Another object is to provide a receptacle of the above-mentioned type adapted particularly for use on a dressing table and hence readily adaptable to ornamental configuration without detracting from the mechanical features and advantages of the device. Another object is to provide a receptacle of the above-mentioned character that will be of simple construction and reliable action and capable of rapid and inexpensive manufacture. Other objects will be in part obvious or in part pointed out hereinafter.

25 The invention accordingly consists in the features of construction, combinations of elements, and arrangements of parts as will be exemplified in the structure to be hereinafter described and the scope of the application 30 of which will be indicated in the following claims.

In the accompanying drawing, in which are shown two of various possible embodiments of the mechanical features of this invention,

35 Figure 1 is a plan view of a receptacle and cover therefor in assembled relation;

Figure 2 is a vertical section taken on the line 2—2 of Fig. 1, and

40 Figure 3 is a vertical section taken on the line 3—3 of Fig. 2.

Figure 4 is a bottom view of the cover of the receptacle, and

Figure 5 is a front elevation of the cover.

45 Figure 6 is a sectional view similar to that of Fig. 2 illustrating a preferred form of embodiment of certain other features of my invention.

Similar reference characters refer to similar parts throughout the several views in the 50 drawing.

This application is a continuation in part of my application Serial No. 22,071, filed April 10, 1925.

55 As conducive to a clearer understanding of this invention, it may at this point be noted

that certain cosmetics each with a device for applying it find most frequent use in the lady's boudoir; these cosmetics are generally intended to be applied successively, and generally the effect produced by one is incomplete 60 without the effect produced by another. For example, the lipstick may readily enough be made to bring out the desired effect in so far as the lips alone are concerned, but the ensemble effect might be anything but the desired one were not a cosmetic such as rouge applied to the face; but even the effect produced by the rouge and the lipstick might be and generally is in turn modified to bring about the intended ensemble effect by tempering the application of rouge with powder. A dominant aim of this invention is to provide a receptacle in which, for example, the three cosmetics pointed out by way of example may be not only conveniently concentrated, but also made readily and conveniently accessible for prompt and quick application.

Referring now to the drawing and more particularly to Figures 1 and 2, there is generally indicated at 10 a receptacle which is in general of an elongated shape and which is provided with several compartments; these compartments may and preferably do comprise a central compartment 11 and an end compartment 12, each preferably circular and the former preferably of larger diameter than the latter. In the compartment 11 may be placed a supply of powder 13, preferably in the form of a compact, and the compartment 11 is of such depth that it may comfortably receive therein the powder puff 14. In the compartment 12 may be placed such a cosmetic as rouge, indicated at 15, and preferably in the form of a compact, and the compartment 12 is of such a depth as to conveniently receive the rouge-applying device or puff 16.

Upon that side of the compartment 11 remote from the compartment 12 the receptacle 10 is provided with a compartment 17 extending transversely of the receptacle 10 and open-ended preferably at both ends thereof. The compartment 17 may conveniently be formed in the shape of a slot extending transversely of the receptacle 10, and is preferably rounded so as to snugly receive a lipstick 18. In order that the entire device be relatively small and compact, the length of the slot or compartment 17 in a direction

transversely of the receptacle 10 preferably approximates the length of the standard lipstick.

The receptacle 10 is provided with a cover 19 the contour of which closely approximates or is coincident with the contour of the receptacle 10, the lid or cover 19 being provided with a handle 20. The lid 19 is preferably flat and in order to center the cover 19 upon the receptacle 10 the cover 19 is provided upon the under face thereof with a member generally indicated at 21, which is arranged to project inwardly into the compartment 11; the member 21 is preferably in the form of a mirror (see also Figs. 4 and 5) and while serving to center the cover 19 with respect to the receptacle 10 when it is desired to close the latter, the mirror 21 forms an important accessory in the use of the entire device, it being noted that the handle 20 permits the convenient manipulation or holding of the mirror 21 as desired.

In order to close the open ends of the compartment 17 which receives the lipstick, the cover 19 is provided at its right-hand end, as viewed in Figures 1, 2, 4 and 5, with two depending lugs 22 and 23 shaped so as to be fitted and received within the ends of the compartment 17, so as to close the latter and hence to seal the lipstick against exposure. The depending lugs 22 and 23 thus not only close the compartment 17 but, in registering within the ends of the slot or compartment 17, they act to prevent rotary displacement of the cover 19 where the central compartment 11 is circular, as is preferably the case in order that it may conform to the standard shape and size of powder puffs. If desired, the lid or cover 19 may be provided with another member 24 on its under face and at the left-hand end thereof, the member 24 being arranged to project into the compartment 12, thus effectively to prevent undesired displacement of the cover 19 with respect to the receptacle 10. This latter feature of construction is of particular advantage where the parts are made of such materials as porcelain, china or glass, for example, which do not readily lend themselves to great accuracy of forming, pressing or molding.

In the use of the receptacle, the removal of the cover 19 not only makes the mirror 21 at once available, but also opens the ends of the slot or compartment 17, permitting the lipstick 18 to be readily and conveniently removed therefrom; this removal may take place by merely sliding the lipstick 18 out of the slot 17, or by grasping the lipstick between the thumb and forefinger of the hand at its now freely exposed ends. The remaining cosmetics and their applying devices, together with the lipstick, may thereupon be used as desired, it being noted that the replacement of the lid or cover 19 closes the open ends of the slot 17, so that the assem-

bled device then presents a solid and unbroken appearance.

Referring now to Figure 6 of the drawing, I have illustrated in a sectional view substantially similar to that of Figure 2, a preferred form of embodiment of certain other features of my invention.

As hereinbefore noted, the supply of powder 13 in the compartment 11 of Figure 2 and the cosmetic such as the rouge indicated at 15 in the compartment 12 are preferably in the form of a compact. It will be understood, however, that such cosmetics as these, and particularly the supply of powder 13, may be in the form of loose powder. A serious disadvantage, however, in using loose powder in a receptacle or compartment resides in the fact that the powder puff rests directly upon the loose powder so that when the powder puff is removed in order to make an application of powder, the puff has adhering to it too great a supply of loose powder. The excess powder, therefore, has to be shaken off or otherwise removed, and this procedure results in not only troublesome manipulation but also loss of powder and in untidiness. Moreover, this disadvantage results in the further defect that precision or nicety of application of the powder to the face are substantially precluded. These defects and disadvantages have given rise to various cumbersome expedients in the endeavor to avoid these disadvantages and have generally resulted in necessitating complicated added parts to the apparatus, thus increasing the cost of manufacture and making more complicated the manipulation and use of the apparatus. A dominant aim of my invention is to avoid in a simple and thoroughly practical and efficient manner such troublesome defects as have just been noted.

Turning now to Figure 6 of the drawing, one of the cosmetic-receiving compartments I have illustrated as embodying my invention and more particularly the central compartment 11, noted above in connection with Figures 1-5, as being the powder-receiving compartment. This compartment, as noted above, is conveniently of substantially circular form though it will be understood that it may be given any other suitable shape in this respect. The supply of loose powder is indicated at 13^a in the compartment 11 of the receptacle 10. The side wall or walls of the compartment 11 are shown as provided with a ledge 11^a preferably extending about and adjacent the upper inside periphery of the side walls of the compartment 11. The powder puff is indicated at 14^a and is of such a size that, when placed in the compartment 11, it rests upon the ledge 11^a.

The vertical height of the ledge 11^a from the bottom of the compartment 11 is preferably so proportioned with respect to the

thickness of the powder puff 14^a that an ample supply of loose powder may be placed in the compartment 11 while the operative portions of the powder puff just conveniently 5 clear the upper surface of the supply of loose powder 13^a, the ledge 11^a thus preventing the powder puff 14^a from resting directly upon the loose powder. The ledge 11^a is spaced in a downward direction from the extreme up- 10 per edge of the compartment 11 by a distance appropriate to accommodate between the cover of the receptacle 10 and the ledge 11^a the main body portion of the powder puff. Thus, when the apparatus is not in use, the powder 15 puff is effectively held out of contact with the supply of loose powder.

In the use of the apparatus and upon the cover being removed from the receptacle 10, the powder puff is thus exposed and may be 20 gripped by the hand. A slight inward or downward pressure upon the powder puff suffices to bring the powder puff into contact with the loose powder 13^a and this downward pressure may be gauged with such a fine degree 25 of nicety that the desired quantity of powder is picked up by the powder puff. After the powder puff has served its purpose its replacement in the compartment 11 results in positioning the powder puff on the ledge 30 11^a, the powder puff, as will be understood from the foregoing, having a sufficient degree of rigidity to be held in the position substantially as shown in Figure 6 and out of contact with the loose powder.

35 It will thus be seen that there has been provided in this invention a receptacle for cosmetics and applying devices therefor in which the several objects hereinbefore noted and many thoroughly practical advantages 40 are achieved. The depending lugs 22-23 of the form of my invention shown in Figure 2, permit the mirror to be set down with the handle uppermost, and prevent contact of the mirror with the surface upon which the cover 45 is thus set. It will be seen that the receptacle is of a construction that lends itself readily to rapid and inexpensive manufacture out of any suitable or desirable material, and when in use is of efficient action in making readily 50 and conveniently available the desired device or devices. More particularly, it will be seen that the lipstick may be compactly housed but without detriment to its rapid and convenient removal manually when the cover of the receptacle is removed. It will furthermore be 55 seen that the apparatus is well adapted for use in connection with loose powder and that the many disadvantages otherwise attendant upon the use of a powder puff in combination with loose powder are effectively avoided and many thoroughly practical advantages 60 achieved.

As many possible embodiments may be 65 made of the above invention, and as many changes might be made in the embodiment

above set forth, it is to be understood that all matter hereinbefore set forth or shown in the accompanying drawings, is to be interpreted as illustrative and not in a limiting sense.

I claim as my invention:

1. A receptacle having a compartment for receiving a cosmetic such as powder and an applying device therefor such as a powder puff, and having another compartment for receiving a lipstick, said latter compartment being in the form of a slot extending transversely of the compartment and open-ended laterally of said receptacle, and a cover for said receptacle having two oppositely disposed depending members adapted to fit into the respective ends of said slot for closing said last-mentioned compartment. 70

2. A receptacle having a compartment for receiving a cosmetic such as powder and an applying device therefor such as a powder puff, and having another compartment for receiving a lipstick, said latter compartment being in the form of a slot extending transversely of the compartment and open-ended laterally of said receptacle, a cover for said receptacle having two oppositely disposed depending members adapted to fit into the respective ends of said slot for closing said last-mentioned compartment, and a mirror mounted upon the under face of said cover and arranged to project into one of said compartments, thereby to hold said cover against displacement with respect to the receptacle. 90

3. A receptacle having a compartment for receiving a device such as a powder puff and having another compartment for receiving a lipstick, said latter compartment having an open end exposed laterally of said receptacle, a cover for said receptacle having means adapted to project into said first compartment to register said cover with respect to said receptacle, and means carried by said cover for closing said open end of said second-mentioned compartment upon said cover being placed in closed position relative to said receptacle. 100

4. A receptacle having a central compartment for receiving a cosmetic and a powder puff, an end compartment for receiving another cosmetic and a puff therefor, and another end compartment shaped to receive a lipstick and having its ends opening laterally of said receptacle, a cover for said receptacle, means on said cover adapted to be received within said puff-receiving compartments for holding said cover against displacement, and means on said cover adapted when the latter is in closing position to close the ends of said lipstick compartment. 115

5. A receptacle having a compartment for receiving a device such as a powder puff and having another compartment for receiving a lipstick, said latter compartment having an open end exposed laterally of said receptacle, a cover for said receptacle, and means car- 120 125 130

ried by said cover and adapted, when said cover is placed in closing position relative to said receptacle, to substantially fit into and close the open end of said last-mentioned compartment.

6. A receptacle having a compartment providing an upwardly open and unobstructed space therein for receiving a cosmetic such as powder, a cosmetic-applying device such as a powder puff, said device being flexible but having sufficient rigidity to permit of its being supported at its lateral edge, and means for supporting said device substantially at edge portions thereof in said compartment and positioned to normally hold said device out of contact with the cosmetic in said compartment, said device being adapted, upon flexing thereof, to be brought into contact with the cosmetic.

7. A receptacle having a compartment providing an upwardly open and unobstructed space therein for receiving a cosmetic such as powder, a cosmetic-applying device such as a powder puff, said device being flexible but having sufficient rigidity to permit of its being supported at its lateral edge, said compartment having projecting means at substantially oppositely disposed portions of its side walls for normally supporting said device at substantially edge portions of the latter and out of contact with the cosmetic, said projecting means being so related to said compartment as to permit said device, upon being flexed downwardly, to be brought into contact with the cosmetic in said compartment.

8. A receptacle having a compartment providing an upwardly open and unobstructed space therein of substantially circular shape for receiving a cosmetic such as powder, and a cosmetic-applying device, also of substantially circular shape, such as a powder puff,

said device being flexible but having sufficient rigidity to permit of its being supported at its lateral edges, said compartment having a lower portion, in which the cosmetic is received, of a diameter less than that of said device, whereby the latter is normally held out of contact with the cosmetic, and an upper portion of a diameter sufficient to receive said device.

9. A vanity box made of a moldable material and shaped to provide a compartment providing an upwardly open and unobstructed space therein for receiving a cosmetic such as powder, and a cosmetic-applying device such as a powder puff, said device being flexible but having sufficient rigidity to permit of its being supported at its lateral edge portions, the walls of said compartment having integrally formed therewith inwardly projecting means upon which said device is adapted to rest substantially at the edge portions of the latter, thereby to hold said device out of contact with the powder in said compartment.

10. A vanity box having a compartment providing an upwardly open and unobstructed space therein for receiving a cosmetic such as loose powder, a cosmetic-applying device such as a powder puff, said device being yieldable, and rigid means projecting upwardly from the bottom of said compartment and providing a support for normally holding said applying device out of contact with the powder in said compartment and adapted upon depression of said yieldable device to permit the latter to be brought into contact with the powder in said compartment.

In testimony whereof, I have signed my name to this specification this 6th day of December, 1926.

LAURA L. MILLRING.
